Primary Examiner—Louis S. Zarfas*Assistant Examiner*—Frank Martinez*Attorney, Agent, or Firm*—Wagner & Middlebrook**[57]****CLAIM**

The ornamental design for an exhaust pipe system for motorcycle, as shown and described.

DESCRIPTION

FIG. 1 is a perspective view of the exhaust pipe system for a motorcycle showing my new design;

FIG. 2 is a right side elevation view thereof;

FIG. 3 is a front elevation view thereof;

FIG. 4 is a top plan view thereof;

FIG. 5 is a left side elevation view thereof;

FIG. 6 is a bottom plan view thereof; and,

FIG. 7 is a rear elevation view thereof.

The dotted line showing of a muffler is for illustrative purposes only and forms no part of the claimed design.
